CASTING APPARATUS

Ralph P. Davis, Squantum, Mass., assignor to
Walworth Company, Boston, Mass., a corpora-
tion of Massachusetts

Application September 6, 1950, Serial No. 183,363

10 Claims. (Cl. 22—90)

1

This invention relates to casting apparatus and method and more particularly to metal pouring apparatus and method for use with shell-type molds.

Molds of the thin walled shell-type are comprised of a major portion of an inorganic molding material, such as sand, and a minor portion of a component serving to bind the inorganic material. The completed molds are in two or more matching parts having the form of hard thin shells of substantial strength. The inner faces of the matching parts are smooth and finished whereas the outer surfaces are left in a rough and irregular condition. Consequently, during the casting operation using such molds the common weighting methods for ordinary sand molds cannot be used with any degree of success.

In casting operations using shell-type molds it has been customary to embed the mold parts in a loose, relatively coarse granular material with the intention of enabling the mold to withstand the static pressure of the molten metal. Refractory materials such as steel shot, sand and gravel have been proposed as suitable bedding material to be contained in the pouring box. This expedient does not, however, provide uniform pressure on the mold parts and in some cases is considerably less than the pressure exerted by the molten metal. The resulting separation or distortion of the mold parts during the casting operation causes sufficient nonconformity between the pattern and the casting to render the latter completely useless. Consequently, the desirable features of the shell-type mold have been outweighed by the difficulty of producing satisfactory castings with such molds.

An object of the present invention is to support shell-type molds during the casting operation under substantially uniform pressure throughout the area thereof and sufficient to prevent separation or distortion of the mold parts.

Another object of the invention is to adjust the pressure on the molds in order to approximate or exceed the static pressure of the metal poured into the mold.

Another object of the invention is to remove the supporting material from the pouring box in an expeditious manner after the casting operation.

The apparatus and method for accomplishing these and other objects and advantages of the invention comprises a pouring box of sufficient dimensions to contain a complete mold in a vertical pouring position. The box is lined on opposite sides with a flexible material, such as a rubber diaphragm, providing a space between the liner and the adjacent wall into which fluid under pressure may be admitted. Thus, the diaphragm becomes distended toward the mold from each side and contacts the approximate area

2

thereof with a uniform pressure which may be as great or greater than the static pressure of the casting material to be poured into the mold.

In order to protect the diaphragm from the heat of the mold an intermediate material may be used such as steel shot, sand or gravel. This material is poured into the space between the mold and the diaphragm with the mold located approximately midway between the opposite sides of the pouring box. The fluid pressure on the diaphragms is thus transmitted through the intermediate material to the molds without losing any advantages of this invention.

The intermediate material may be easily removed from the box after the casting operation by the use of fluid pressure or suction applied to the bottom of the box at the appropriate time. The box may be specially formed to facilitate the shot withdrawal even when the box is completely full.

In the accompanying drawings:

Fig. 1 is a plan view of the metal pouring apparatus showing a mold in position therein;

Fig. 2 is a cross-section taken on the line II—II of Fig. 1;

Fig. 3 is a longitudinal section taken on the line III—III of Fig. 2, and

Fig. 4 is an enlarged sectional view taken on the line IV—IV of Fig. 1.

Referring more particularly to the drawing, the pouring box 9 comprises a generally rectangular casing 10 having an open end 12 and a centrally disposed, hollow partition 14. The partition 14 serves to divide the casing 10 longitudinally into two halves, each of which is adapted to contain a mold. As indicated in Fig. 1 by a broken line 16 a shell-type mold comprised of two matching parts is positioned in one of the halves of the pouring box. It will be apparent that a similar or different mold could be positioned in the other half of the casing 16. Moreover, while a double pouring box is shown and described herein, a single box could be used if desired. The length and width of the casing 10 as viewed in Fig. 3 are greater than those of the mold 16 which is inserted freely in an edgewise direction through the open end 12. It will be observed that the depth of the casing 10 on each side of the partition 14, as viewed in Fig. 1, and defined by the opposite side walls of the casing 10 and partition 14 is sufficient to space these walls from the molds 16. An aperture 18 is provided preferably at one end in each of the side walls of the casing 10 and the partition 14 respectively for a purpose apparent hereinafter.

Each half of the pouring box 9 contains a pair of liners 20 of generally rectangular form which are secured at their marginal edges to the adjacent side walls of the casing 10 and partition 14 respectively. The securing means for the

liners 20 may take the form of rivets 22, although bolts or other securing means may equally well be used. The liners 20 are preferably made of flexible sheet material, such as rubber, although any other resilient or elastic material may be employed. Interposed between each of the liners 20 and the adjacent walls of the casing 10 and partition 14 is an annular spacer or gasket 26 of rubber or similar resilient material. A retaining ring 28, preferably of metal or other hard material, is superimposed on each of the liners 22 to provide a firm surface for the rivets 22. In this manner, the liners 22 are spaced from the adjacent walls of the casing 10 and partition 14 to provide four chambers 24 which are sealed around the edges by the fastening means described to close the chambers 24 thus provided. A plurality, in this instance four angle bars 30 extend transversely across each half of the pouring box 9 opposite the open end 12 and may each be secured at one end to the side walls of the casing 10 and at the opposite end to the partition 14 by welding or other suitable means. As shown more clearly in Fig. 3 each of the angle bars 30 has the open portion of the angle facing away from the open end 12 of the pouring box 9, thus presenting a pair of inclined surfaces toward the open end 12. As will be apparent, the mold 16 may be positioned on the angle bars 30 in pouring position and supported thereby during subsequent operations.

Closure means 32 in the form of an elongated, funnel-shaped member is provided for the end of the casing opposite the open end 12. The closure means 32 conforms to the side and end walls of the casing 10 and may be integral with these walls as shown or may be formed as a separate part secured thereto if desired. The closure means 32 has an outlet 34 in the form of a slot extending longitudinally of the neck of this funnel-shaped member. An exhaust pipe 36 extends longitudinally of the closure means 32 and is provided with an elongated recess 38 for the reception of the outlet 34. Preferably, the walls of the recess 38 are welded or otherwise secured to the side walls of the closure member 32 with the outlet 34 positioned substantially coincident with the axis of the pipe 36 for a purpose apparent hereinafter.

Means for admitting fluid under pressure to the chambers 24 are provided and take the form of a plurality, in this instance four, elbows 40 one pair being secured as by welding to the exterior side walls of the casing 10 on opposite sides thereof and the other pair located within the hollow partition 14 for communication with the apertures 19 in the side walls. The elbows 40 connect with suitable piping 42 which communicates with a source of fluid pressure (not shown), such as compressed air, through a multi-way valve 44 having an inlet 46 and an exhaust 48 associated therewith. In order that the pressure admitted to the chambers 24 may be set to a desired value, a suitable pressure regulator 50 may be included in the inlet 46 for this purpose. It will be understood that separate valves 44 can be provided to control the flow of fluid in the piping 42 to each half of the pouring box 9 or a single valve 44 may control the flow to both halves.

In order to protect the flexible liners 20 from the heat of the molten metal transmitted through the mold 16, an intermediate material is used between the liners 20 and the mold 16. This material is of a granular nature such as

5 steel shot, sand or gravel and is pourable through the open end 12 after the mold 16 is positioned in the casing 10. As shown in Fig. 1, the mold 16 is located approximately midway between the liners 20 in one-half of the pouring box 9 and the granular material, indicated by the reference numeral 52, completely fills the surrounding space. It will be apparent that the closure means 32 will also become filled with the granular material 52 and will flow from the outlet 34 into the pipe 36. However, since the outlet 34 is positioned substantially coincident with the axis of the pipe 36 then the latter will not be completely blocked by the granular material even when the casing 10 is completely filled. In some cases it may be advantageous to insert a rigid plate of metal or other suitable material between the flexible liners 20 and the granular material 52 depending upon the type of mold 16 which is to be poured. Moreover, water or other liquid or gas may be used to fill the chamber 24 if desired.

15 The casing 10 is provided with a plurality, in this instance four, locating lugs 54 one at each corner and suitably perforated to receive retaining bolts or the like (not shown) by means of which the casing may be secured to a foundation, as indicated by the broken line 56 in Figs. 2 and 3. When so positioned, the closure means 32 and the pipe 36 may be contained in a pit or other depression 58 in the foundation 56 below the securing means for the pouring box 9.

OPERATION

35 In the operation of the apparatus, the mold 16 may be inserted edgewise into one of the spaces in the casing 10 between the side wall and the partition 14. As previously noted, the bottom edge of the mold rests on the angle bars 30 and is positioned approximately midway between the 40 partition 14 and the side wall of the casing 10 and spaced from the end walls thereof. While so positioned, the space around the mold 16 is filled with the intermediate material such as steel shot, which will serve to support the mold 16 in the desired location. Thereafter, fluid under 45 pressure is admitted by operation of the valve 44 to the chambers 24 on each side of the mold 16 thereby compressing the mold 16 sufficiently to withstand the static pressure of casting metal 50 which can then be poured in molten condition into the mold 16 in the usual manner. The pressure of the fluid can be set to approximate or be greater than the static pressure of the metal 55 poured into the mold 16 so that no separation or distortion of the mold parts can occur.

Upon termination of the pouring operation and cooling of the casting metal, the valve 44 is operated to exhaust the pressure fluid in the chambers 24. The steel shot can then be expeditiously 60 removed by application of suction to the pipe 36 which will carry the shot to a common sump (not shown). The arrangement of the outlet 34 within the pipe 36, as previously described, makes it possible for the suction fluid to reach high 65 velocity even when the casing 10 is filled with the refractory material, since the pipe 36 itself cannot become completely filled or blocked.

70 It will be apparent that casting apparatus for use in pouring molds having an irregular exterior surface has been provided and that the desirable features of shell-type molds are preserved during the casting operation. It will further be apparent that many changes may be made in the details of construction and arrangement of 75 parts and in the steps of the method without

departing from the scope of the invention as defined in the appended claims.

I claim:

1. Casting apparatus for a shell-type mold, comprising a casing having an area adapted to contain the mold, said casing having a depth defined by opposite side walls adapted to be spaced from the mold, a pair of flexible liners extending across said opposite walls and forming therewith a pair of closed chambers within said casing, granular material contained between said spaced mold and opposite side walls, and means for admitting fluid under pressure to said chambers to distend said liners relative to said opposite walls, said liners being thereby cooperable with said granular material and adapted to compress the mold sufficiently to withstand the static pressure of casting material during the casting operation.

2. Casting apparatus as defined in claim 1 wherein said casing is generally rectangular having an open end, said liners being of generally rectangular form secured at the marginal edges to the adjacent side walls, said side walls having apertures therein with which said means for admitting fluid communicate.

3. Casting apparatus for a shell-type mold, comprising a casing having an area adapted to contain the mold, said casing having a depth defined by opposite side walls adapted to be spaced from the mold, a pair of flexible liners extending across said opposite walls and forming therewith a pair of closed chambers within the casing, granular material contained between said spaced mold and opposite side walls, closure means for one end of said casing having an outlet therein for said granular material, means for admitting fluid under pressure to said chambers to distend said liners relative to said opposite side walls, said liners being thereby cooperable with said granular material and adapted to compress the mold sufficiently to withstand the static pressure of casting material during the casting operation, and means operable for withdrawing said granular material from said outlet upon termination of said casting operation.

4. Casting apparatus as defined in claim 3 wherein said withdrawing means comprises a suction pipe communicating with said aperture.

5. Casting apparatus as claimed in claim 4 wherein said closure means are connected to said pipe with said outlet substantially coincident with the axis of said pipe to prevent blocking thereof by said material.

6. Casting apparatus for a shell-type mold, comprising a generally rectangular casing having an open end and a length and width adapted to contain the mold inserted through said open end, said casing having a depth defined by opposite side walls adapted to be spaced from the mold, a pair of flexible liners of generally rectangular form secured at the marginal edges to the adjacent side walls and forming therewith a pair of closed chambers within said casing, granular material contained between said spaced mold and opposite side walls, said material being refractory and pourable through said open end, closure means for the opposite end of said casing having an elongated outlet therein for said granular material, means for admitting fluid under pressure to said chambers to distend said liners away from said opposite side walls, said liners being thereby cooperable with said granu-

lar material and adapted to compress the mold sufficiently to withstand the static pressure of casting material during the casting operation, and a suction pipe extending substantially parallel with said closure means and having an elongated recess for receiving said outlet substantially coincident with the axis of said pipe to prevent blocking thereof by said material.

7. Casting apparatus for shell-type molds, comprising a generally rectangular casing having an open end and a centrally disposed partition, said casing having a length and width adapted to contain a mold on each side of the partition inserted through said open end, said casing having a depth defined by opposite side walls of said casing and partition adapted to be spaced from the molds, a pair of flexible liners of generally rectangular form secured at the marginal edges to the adjacent side walls of said casing and partition respectively and forming therewith a pair of chambers on each side of said partition within said casing, granular material contained between said spaced molds and opposite side walls, said material being refractory and pourable through said open end, a funnel-shaped closure means for the opposite end of said casing having an elongated outlet therein for said granular material, means for admitting fluid under pressure to said chambers to distend said liners away from said opposite side walls, said liners being thereby cooperable with said granular material and adapted to compress the molds sufficiently to withstand the static pressure of casting material during the casting operation, and a suction pipe extending substantially parallel with said closure means and having an elongated recess for receiving said outlet substantially coincident with the axis of said pipe to prevent blocking thereof by said material.

8. A method of casting with shell-type molds comprising inserting a mold substantially midway between spaced oppositely disposed flexible surfaces, positioning granular refractory material in said spaces between the mold and said surfaces, and applying fluid under pressure to said surfaces to distend the same and compress the granular material toward said mold for supporting said mold during the casting operation under substantially uniform pressure at least equal to the static pressure of the casting material.

9. The method as claimed in claim 8 wherein said granular material is poured in said spaces between the mold and said flexible surfaces to completely fill the same.

10. The method as claimed in claim 9 wherein said fluid pressure is released following said casting operation and thereafter said granular material is withdrawn by suction from said spaces.
